CLAIM

The ornamental design for a nightstand, as shown and described.

DESCRIPTION

FIG. 1 is a left, front perspective view of the nightstand according to a first embodiment showing a drawer in a closed position;
FIG. 2 is a right, front perspective view thereof;
FIG. 3 is a front view thereof;
FIG. 4 is a left side view thereof;
FIG. 5 is a rear view thereof;
FIG. 6 is a right side view thereof;
FIG. 7 is a top view thereof;
FIG. 8 is a left, front perspective view thereof, showing the drawer in an opened position;
FIG. 9 is a right, front perspective view thereof, showing the drawer in an opened position;
FIG. 10 is a front view thereof, showing the drawer in an opened position;
FIG. 11 is a left side view thereof, showing the drawer in an opened position;
FIG. 12 is a rear view thereof, showing the drawer in an opened position;
FIG. 13 is a right side view thereof, showing the drawer in an opened position;
FIG. 14 is a top view thereof, showing the drawer in an opened position;
FIG. 15 is a left, front perspective view of the nightstand according to a second embodiment showing a drawer in an opened position;
FIG. 16 is a right, front perspective view thereof;
FIG. 17 is a front view thereof;
FIG. 18 is a left side view thereof;
FIG. 19 is a rear view thereof;
FIG. 20 is a right side view thereof;
FIG. 21 is a top view thereof;
FIG. 22 is a left, front perspective view of the nightstand according to a third embodiment showing a drawer in a closed position;
FIG. 23 is a right, front perspective view thereof;
FIG. 24 is a front view thereof;
FIG. 25 is a left side view thereof;
FIG. 26 is a rear view thereof;
FIG. 27 is a right side view thereof;
FIG. 28 is a top view thereof;
FIG. 29 is a left, front perspective view thereof, showing the drawer in an opened position;
FIG. 30 is a right, front perspective view thereof, showing the drawer in an opened position;
FIG. 31 is a front view thereof, showing the drawer in an opened position;
FIG. 32 is a left side view thereof, showing the drawer in an opened position;
FIG. 33 is a rear view thereof, showing the drawer in an opened position;
FIG. 34 is a right side view thereof, showing the drawer in an opened position;
FIG. 35 is a top view thereof, showing the drawer in an opened position;
FIG. 36 is a front perspective view of the nightstand according to a fourth embodiment showing a drawer in an opened position;
FIG. 37 is a right, front perspective view thereof, showing the drawer in an opened position;

FIG. 38 is a front view thereof, showing the drawer in an opened position;
FIG. 39 is a left side view thereof, showing the drawer in an opened position;
FIG. 40 is a rear view thereof, showing the drawer in an opened position;
FIG. 41 is a right side view thereof, showing the drawer in an opened position;
FIG. 42 is a top view thereof, showing the drawer in an opened position;
FIG. 43 is a left, front perspective view of the nightstand according to a fifth embodiment showing a drawer in a closed position;
FIG. 44 is a right, front perspective view thereof;
FIG. 45 is a front view thereof;
FIG. 46 is a left side view thereof;
FIG. 47 is a rear view thereof;
FIG. 48 is a right side view thereof;
FIG. 49 is a top view thereof;
FIG. 50 is a left, front perspective view thereof, showing the drawer in an opened position;
FIG. 51 is a right, front perspective view thereof, showing the drawer in an opened position;
FIG. 52 is a front view thereof, showing the drawer in an opened position;
FIG. 53 is a left side view thereof, showing the drawer in an opened position;
FIG. 54 is a rear view thereof, showing the drawer in an opened position;
FIG. 55 is a right side view thereof, showing the drawer in an opened position;
FIG. 56 is a top view thereof, showing the drawer in an opened position;
FIG. 57 is a front perspective view of the nightstand according to a sixth embodiment showing a drawer in an opened position;
FIG. 58 is a right, front perspective view thereof, showing the drawer in an opened position;
FIG. 59 is a front view thereof, showing the drawer in an opened position;
FIG. 60 is a left side view thereof, showing the drawer in an opened position;
FIG. 61 is a rear view thereof, showing the drawer in an opened position;
FIG. 62 is a right side view thereof, showing the drawer in an opened position; and,
FIG. 63 is a top view thereof, showing the drawer in an opened position.
The fragmentary showing of wood graining in FIGS. 1-4, 6, 8-11, 13, 15-18, 20, 22-25, 27, 29-32, 34, 36-39, and 41 is understood to be repeated throughout the surface(s) shown. The broken lines in the drawings depict portions of the article that form no part of the claimed design. In FIGS. 8, 9, 14, 29, 30, 35, 50, 51, and 56, the flashlight shown in broken lines depicts environment and forms no part of the claimed design.
